United States Patent Office

Des. 221,677
Patented Aug. 31, 1971

221,677

STAND FOR NAPKINS OR THE LIKE

Charles H. Losh, White St. Extension,
Leominster, Mass. 01453

Filed Sept. 22, 1969, Ser. No. 19,229

Term of patent 14 years

Int. Cl. D7—06

U.S. Cl. D44—24

FIG. 1

FIG. 2

FIG. 3

FIG. 1 is a front elevation of a stand for napkins or the like showing my new design;

FIG. 2 is a top plan view thereof, and
FIG. 3 is a bottom plan view thereof.

I claim:

The ornamental design for a stand for napkins or the like.
